UNITED STATES PATENT OFFICE.

OTTO J. GROEHN, OF DETROIT, MICHIGAN, ASSIGNOR TO CLAYTON AND LAMBERT MANUFACTURING COMPANY, OF DETROIT, MICHIGAN, A CORPORATION OF MICHIGAN.

TORCH BURNER.

Application filed October 2, 1920. Serial No. 414,257.

To all whom it may concern:

Be it known that I, OTTO J. GROEHN, a citizen of the United States of America, residing at Detroit, in the county of Wayne and State of Michigan, have invented certain new and useful Improvements in Torch Burners, of which the following is a specification, reference being had therein to the accompanying drawings.

10 This invention relates to oil burners or the like and refers more particularly to that class of burners used in connection with blow torches or like tools. It is one of the objects of the invention to provide a construction in which the burner is prevented from clogging or more particularly to provide a means for cleaning the discharge nozzle of the burner so that it can be readily maintained in operative condition. Another 15 important feature of the invention is to provide a cleaning needle or like member which is not only attached to the tool and readily available for use but which is so constructed and arranged that the user cannot force the 20 cleaning needle in such a way as to injure the discharge orifice.

The invention also contemplates a novel combination wherein the valve which controls the supply to the discharge orifice is 25 located at a point distant from the discharge orifice; the cleaning needle being used solely for cleaning the discharge orifice and preferably so constructed that it cannot perform the function of the valve. Still another object of the invention is to provide an improved preheating arrangement for vaporizing the fuel before it reaches the discharge orifice of the burner and in such further features of construction and arrangements and 30 combinations of parts as will more fully hereinafter appear.

In the drawings:

Figure 1 is a side elevational view partly in section of a blow torch having a burner embodying my invention;

Figure 2 is a view taken at right angles to Figure 1 on the line 2—2 of Figure 1;

Figure 3 is a cross-sectional view taken at right angles to Figure 1 on the line 3—3 of 50 Figure 1.

Describing in detail the invention as applied to a blow torch, A designates the burner of a blow torch which comprises in addition to the burner the supply tank B having the

standard B' connecting the burner to the tank and a suitable pump B² for forcing the liquid fuel through the inlet C of the chamber to the vaporizing chamber C'. This latter chamber is preferably cast integral and located adjacent to the combustion chamber D so that the heat radiated from the combustion chamber D through the wall D' will heat the fuel in the vaporizing chamber C' thus assisting in vaporizing it. Also if desired, suitable fine wire mesh screen or other filtering material C² is employed for both assisting in vaporizing the fuel and filtering the same to keep the free carbon removed therefrom. Within the vaporizing chamber C' there is located a fuel passage-way E which is tapered at its inlet E' and at its opposite end is provided with a valve port F controlled by a suitable valve such as the needle valve F'. It will be noticed that this tube E which forms a fuel passage-way is offset at G so that its upper wall G' lies substantially adjacent the lower wall D' of the combustion chamber D. This is an important feature in that the fuel being vaporized in the chamber C' is compelled to pass through the tube E directly adjacent to the hot wall of the combustion chamber and thereby being subjected to a greatly increased vaporizing effect. After passing through the port F the vaporized fuel passes upward through the vertical passage-way H' to the discharge orifice H. This last-mentioned orifice is preferably cylindrical in shape and is formed in a removable fitting I which is screw threaded at I' into the burner fitting. Extending in axial alignment with this orifice, but in the opposite direction, is a threaded nipple portion J' through which the stem J² of the cleanout needle J is threaded. This needle is operated by a separate hand wheel J³ on the outer end of the stem J².

After passing through the discharge orifice H the fuel mixed with a suitable quantity of air is burned within the combustion chamber D and heretofore great difficulty has been encountered in maintaining the proper relation between the discharge orifice and the burner owing to the fact that a valve mechanism seating with the discharge orifice would be jammed into the latter while it is hot thus distorting the seat and in many cases enlarging the discharge

orifice. Moreover great difficulty has been encountered in maintaining a valve at this point owing to the extreme heat at this portion of the burner. In the present construction these disadvantages are avoided by not only locating the shut-off valve at a point in the passage-way somewhat remote from the discharge orifice but also by arranging the cleanout needle J so that it cannot perform the function of the valve. For this purpose there is provided an abutment or stop which will prevent the end K of the steam J^2 from being forced into contact with the metal surrounding the discharge orifice H . In the particular construction shown this stop or abutment is formed by terminating the threads J^4 on the stem J^2 a sufficient distance from the hand wheel J^3 that the forward movement of the needle J will be terminated by the shoulder portion L striking against the metal of the interiorly threaded portion L' before the end K reaches the metal portion surrounding the orifice H . The proportioning of parts, however, is such that the needle J will be projected entirely through the discharge orifice H and this needle is preferably of the same cross-sectional area as the interior of the discharge orifice H . Also being in axial alignment with such passage-way the side walls of the cleanout needle will be in all positions of adjustment substantially parallel to the side walls of the discharge orifice H thereby preventing any pressure being exerted upon the metal surrounding the discharge orifice. The invention in its broader aspects is not limited to the cleanout needle J being of the same or cross section as the discharge orifice of the burner, but I consider it of great importance that the cleanout needle should be arranged to be incapable of use as a valve and that the mechanism be so arranged that the user cannot jam or force the cleanout needle or its associated mechanism in contact with the metal surrounding the discharge orifice in such a way as to injure or alter the latter.

A torch having a burner construction as above described is capable of use as both

a gasoline or kerosene torch or for other types of vaporizing fuel and disarrangement of the torch due to clogging by carbon is avoided in that the operator at all times has in convenient position for use the cleanout needle which can be instantly moved to cleaning position and then retracted. Moreover this needle is entirely independent of the shut-off or control valve. I do not, however, desire to limit the invention to the particular details of construction shown and described except as ultimately set forth in the claim.

What I claim as my invention is:

In a blow pipe torch for developing intense heat, a flame tube having an open forward end, a vapor discharge nozzle at the rear end of said tube and having a discharge port substantially in alignment with the axis of the flame tube for discharging fuel into said flame tube to mix with air and burn in said tube, an interiorly threaded portion disposed in rear of said nozzle, a stem extending through said threaded portion and adjustable toward and from said discharge port, said stem and threaded portion being in alignment with the axis of said discharge port, said stem being adapted to be withdrawn from said threaded portion, a cleanout member carried by said stem and adjustable toward and from said discharge port, a vaporizing passage leading from a source of supply of fuel to the port of said discharge nozzle, a valve for controlling the supply of fuel to said vaporizing passage located at a position remote to said discharge nozzle, said valve having a stem provided with an adjustment for positively forcing the valve to its closed position so as to control the supply of fuel to the discharge nozzle independent of the cleanout member, and means for limiting the forward movement of said cleanout member so as to prevent the latter from being forced into contact with the metal surrounding the orifice of the discharge nozzle.

In testimony whereof I affix my signature.

OTTO J. GROEHN.
